SAFETY MECHANISM FOR PUNCH-PRESSES.

1,172,769.

Specification of Letters Patent. Patented Feb. 22, 1916.

Application filed September 21, 1915. Serial No. 51,779.

To all whom it may concern:

Be it known that we, WILLIAM A. D'ARCY and WILLIAM S. ROBERTSON, citizens of the United States, and residents of the city of Rochester, in the county of Monroe and State of New York, have invented a new and useful Safety Mechanism for Punch-Presses and the like, of which the following is a specification.

10 This invention relates to devices for safeguarding the operators of punch presses and of like intermittently operated machinery from injury either by their own carelessness or by a failure of the clutch of the machine 15 to operate properly.

One of the objects of the invention is to devise a simple, durable and reliable safety mechanism for punch presses which will positively prevent the press from accidentally repeating.

20 A further object of the invention is to devise a safety mechanism of the character specified which will prevent the operation of the machine while the operator's hand or 25 arm is in the way of the ram.

Further objects and advantages of this invention will appear more fully hereinafter as the description of the construction and 30 operation of the mechanism embodying the invention progresses.

The invention consists in the parts and in the arrangements and combinations of parts, which will be fully set forth hereinafter.

In the accompanying drawing, in which 35 is illustrated one physical embodiment of the invention and in which like parts are designated by like reference characters in the several views, Figure 1 is a front elevation of a punch press of well known construction showing a safety mechanism embodying the invention applied thereto; Fig. 2 is an enlarged detail section taken substantially on the line 2-2 in Fig. 1, and showing the construction of the clutch mechanism; 40 Fig. 3 is an enlarged detail section taken substantially on the line 3-3 in Fig. 2; Fig. 4 is a side elevation of the punch press and the safety mechanism applied thereto; Fig. 5 is a detail view of a part of the 45 safety mechanism; and Fig. 6 is a section on the line 6-6 in Fig. 3.

Referring to the accompanying drawings, the punch press to which the safety mechanism embodying the invention is applied is 50 of ordinary construction and comprises the usual frame A, the bed plate B, the driving

shaft C, the ram or plunger D, and the driving pulley E, which also acts as a fly wheel. The driving pulley E is journaled loosely on the driving shaft C and is held in place 60 thereon by an end cap 5 fastened to the shaft C by a set screw 5¹ (see Fig. 3).

Punch presses of the type illustrated are usually provided with some form of clutch mechanism which can be actuated by the 65 operator to connect the driving pulley E and the driving shaft C operatively together. In the particular form of clutch mechanism shown in the drawing, a collar 6 is mounted on the shaft C adjacent to the inner face of 70 the hub of the driving pulley E; and in the inner circumferential face of the collar 6 is formed a semi-cylindrical groove 7. A similar cylindrical groove 8 is formed in the shaft; and arranged in this groove 8 in the 75 shaft C is a key or clutch member K comprising a cylindrical end portion 10 journaled in the end cap 5, an intermediate semi-cylindrical portion 11, and an inner end portion 12, substantially segmental in cross section, as shown to the best advantage in Fig.

2. In the hub of the driving pulley E are formed two semi-cylindrical grooves 9 adapted to receive the intermediate portion 11 of the key K, when said key is turned.

80 The key K is operated by a rocker arm 13 which has a laterally projecting end portion 13¹ fitting into the space between the end portion 12 of the rotary key K and the wall of the groove 7 in the collar 6, and which has 85 a hooked end 13². A compression spring 14 is interposed between the rocker arm 13 and a lug or projection 15 fixed to the collar 6.

Fixed to the collar 6 are two stop pins 15¹ and 15² which limit the movement of the 90 rocker arm 13. Below the collar 6 is a lug or projection 16 which is integral with or secured to the frame A of the press and in which is journaled a short shaft 17. To one end of the shaft 17 is fixed a tripper arm 18, arranged to be swung in and out of the path of movement of the hooked end 13² of the 95 rocker arm 13, and to the other end of the shaft 17 is fixed an operating arm 19.

100 The construction so far described forms no part of the present invention, being merely that of a punch press selected as a press suitable for showing the safety mechanism embodying the invention attached thereto. The safety mechanism comprises 105 a lever 20 which has a fulcrum block 21 adjustably secured thereto by a set screw 22,

said fulcrum block being journaled on a suitable pin or stud 23 fixed to the frame A of the press. On the short rear end of the lever 20 is an adjustable counterweight 24, 5 which tends to depress that end of the lever and lift the opposite front end of said lever. A connecting block 25 is mounted on the lever 20 between two pins 26 secured therein, and said connecting block 25 has a slot 10 or a hole therein through which the lever 20 passes, said slot being larger than said lever whereby the connecting block 25 may tilt to some extent relatively to said lever. To the upper end of the connecting block 15 25 is pivoted the lower end of a link 27, the upper end of which is pivoted to the operating arm 19 of the clutch mechanism. Below the lever 20 is a box-like frame 28 which is fastened by an angle bracket 29 to the 20 frame A of the press, and which has guide slots 30 and 31 in its upper and lower end walls; and guided in the upper and lower slots 30 and 31 is a slide 32, which has a pin 34 fixed therein near its upper end adapted 25 to contact with the upper end wall of the frame 28 so as to limit the upward movement of said slide. Part of one edge of the slide 32 is cut away to form a shoulder 35; and fixed in said slide is a pin 36 which extends laterally beyond the planes of the front and back edges of the frame 28. The slide 32 is connected by a rod 33 to the connecting block 25; and is pressed sidewise, that is, to the left in Figs. 4 and 5, by two 30 compression springs 37 which are mounted on studs integral with the adjacent side wall of the frame 28, and which press against a friction plate 38 bearing against the slide 32. Also guided in the upper slot 30 and 35 the lower slot 31 in the frame 28 is an operating plunger 39 which has part of one edge thereof cut away to form a shoulder 40 adapted to coöperate with the shoulder 35 of the slide 32, so as to lock the plunger 39 40 and the slide 32 against endwise movement from each other in one direction. The plunger 39 is connected to a rod 39¹ which is fastened by an adjustable clamp 41 to a link 42, the lower end of which is pivotally 45 connected to the usual treadle 43, said treadle 43 being held in its upper position by a tension spring 44 attached thereto and to the frame A of the press.

Secured to the ram or plunger D of the 50 press is a rearwardly extending arm 45 to which are fastened two downwardly extending cam fingers 46 which straddle the frame 28 in position to contact with the ends of the pin 36 fixed in the side 32, when the ram 55 D is in its lower position. A coupling sleeve 47 is adjustably secured to the front end of the lever 20 by a set screw 48; and adjustably secured to the coupling sleeve 47 by another set screw 50 is a guard supporting arm 49 which extends transversely of the

press and terminates in the vertically slotted head 51 with a clamping set screw 52. The guard comprises a horizontal portion 53 and a stem 54, which stem extends upwardly through the slot in the head 51 of the guard 70 supporting arm 49, and is adjustably held therein by the set screw 52. A clutch restoring lever 55 is journaled on a pin or bolt 56 fixed to the frame D of the press at one side of the ram D, one end of said restoring lever 55 extending under the lever 20, and the other end of said restoring lever fitting into the slot 57 in a bracket or arm 58 rigidly secured to the ram D.

The operation of the press and the safety 80 mechanism is as follows: When the parts are in their normal position, as shown in the drawings, the driving pulley E rotates freely on the driving shaft C; and when the operator wishes to cause the ram D to descend he presses down on the treadle 43, which pulls the link 42, the plunger 39 and the slide 32 downwardly, since the shoulder 40 of the plunger 39 is engaged with the shoulder 35 of the slide 32. The downward 85 movement of the slide 32 pulls down the front end of the lever 20 and forces the horizontal portion 53 of the guard down, and also pulls the link 27 downwardly to throw the tripper arm 18 out of engagement 90 with the rocker arm 13. In this way, the rocker arm 13 and the rotary key K are free to be moved by the spring 14, and as the driving pulley E turns and brings the next recess 9 therein opposite to the rotary key 95 K, the spring 14 turns the key K into this recess in the driving pulley, whereby said driving pulley is rigidly connected to the driving shaft C and moves said shaft to cause the descent of the ram D. The parts 100 are so proportioned that before the tripper arm 18 can be moved far enough to release the rocker arm 13, the horizontal portion 53 of the guard must be pressed to its lowermost position in which it is impossible for the operator to have his hand or arm underneath the ram D. In case the operator should have his hand in the way of the ram D, the horizontal portion 53 of the guard 105 would strike his hand and arrest the movement of the lever 20 and prevent sufficient movement of the link 27 and the tripper arm 18 to release the rocker arm 13 and cause the operation of the clutch mechanism. When the ram D descends the cam fingers 46 carried by the arm 45 strike the pin 36 of the slide 32 and push said slide sidewise against the opposition of the springs 37 so as to release the shoulder 35 in said slide from the shoulder 40 of the plunger 39, whereby 110 the lever 20 is free to be returned to its normal position by the counterweight 24, regardless of whether or not the operator still holds the treadle 43 down. Shortly after the slide 32 is released from the plunger 39, 115 120 125 130

the restoring lever 55 is tilted by the descent of the ram D, and the outer end of said restoring lever 35 engages the under edge of the lever 20 and positively forces the front 5 end of the lever 20 to its upper position, so as to positively move the tripper arm 18 by means of the operating arm 19 and the shaft 17 into the path of movement of the rocker arm 13. When the driving shaft C has completed its revolution the rocker arm 13 strikes the tripper arm 18 and the rotary key K is turned clear of the recess 9 in said driving pulley, thereby permitting said driving pulley to continue its rotation while the 15 driving shaft C remains stationary.

It should be noted that the safety mechanism shown and hereinbefore described positively prevents the press from repeating and also prevents the press from being operated 20 while the hand or arm of the operator is in the way of the ram of the press. In the first place, the tripper arm 18 for operating the clutch mechanism to its unclutched position is positively disconnected from the treadle 25 43 so that the clutch will be unclutched, regardless of whether or not the operator holds down the treadle 43. In the next place, no reliance is placed on the counterweight 24 or on a spring alone for the 30 restoring of the tripper arm 18 to its tripping position; but on the contrary, the lever 20 and the tripper arm 18 are positively actuated by the restoring lever 55 when the ram descends and in ample time for the tripper arm 18 to engage the rocker arm 13. Also, the parts are arranged so that the 35 clutch mechanism cannot be operated to its clutched position while the hand or arm of the operator is under the ram, since it is necessary for the guard to sweep across the 40 space, which would be occupied by the operator's hand or arm, before sufficient movement can be given to the tripper arm 18 to release the rocker arm 13.

Obviously, the safety mechanism embodying the invention may be applied to presses of other constructions than the one shown and to presses having other forms of clutch mechanisms without departing from the invention or from the particular physical embodiment shown and described. If desired, the moving parts of the safety mechanism may be included within any suitable protecting casing or guard which will prevent 50 tampering with the mechanism. Also, other changes may be made in the particular construction shown and described without departing from the invention, and we do not wish to be restricted to the details of the construction and arrangement of the parts shown and hereinbefore described.

What we claim as new and desire to secure by Letters Patent of the United States, is:

1. In a safety mechanism for punch

presses and the like, in combination: a driving shaft; a driving pulley; a ram operated by said shaft; a clutch mechanism for connecting said pulley to said shaft; a treadle; a connection between said treadle and said 70 clutch mechanism comprising disengageable latch members; and means operatively connected to said ram and actuated by the downward movement thereof for disengaging said latch members. 75

2. In a safety mechanism for punch presses and the like, in combination: a driving shaft; a driving pulley; a ram operated by said shaft; clutch mechanisms for connecting said pulley to said shaft; a movable 80 member for operating said clutch mechanism; a treadle; a connection between said treadle and said movable member comprising disengageable latch members; resilient means for restoring said movable member to its position for unclutching said clutch mechanism; means operatively connected to said ram and actuated by the downward movement thereof for disengaging said latch members; and means operatively connected 85 to said ram for positively restoring said movable member to its position for unclutching said clutch mechanism. 90

3. In a safety mechanism for punch presses and the like, in combination: a driving shaft; a driving pulley; a ram operated by said shaft; a clutch mechanism for connecting said pulley to said shaft; a treadle; means operatively connected to said ram and actuated thereby for disconnecting 95 said clutch mechanism and said treadle; and means operatively connected to said ram and actuated by the downward movement thereof for positively returning said clutch to its unclutched position. 100

4. In a safety mechanism for punch presses and the like, in combination: a driving shaft; a driving pulley; a ram operated by said shaft; clutch mechanism for connecting said shaft and said pulley; a treadle; a connection between said treadle and said clutch mechanism comprising disengageable latch members; means operated simultaneously with the downward movement of said ram for disengaging said latch members; a movable guard arranged to sweep the space occupied by the arm or hand of the operator when under said ram; and means for operatively connecting said guard to said treadle, said guard being fully operated before said clutch mechanism is actuated by said treadle to its clutching position. 110

5. In a safety mechanism for punch presses and the like, in combination: a driving shaft; a driving pulley; a ram operated by said shaft; clutch mechanism for connecting said pulley to said shaft; a treadle; a connection between said treadle and said clutch mechanism comprising disengaging 115 latch members; means operatively connected 120 to said treadle, said guard being fully operated before said clutch mechanism is actuated by said treadle to its clutching position. 125

1. In a safety mechanism for punch

4
to said ram and actuated by the downward movement thereof for disengaging said latch members; means operatively connected to said ram for positively restoring said 5 clutch mechanism to its unclutched position; and a movable guard mounted to sweep the space occupied by an operator's hand or arm when under said ram, said guard being operatively connected to said treadle and being 10 fully operated thereby before said clutch mechanism is actuated by said treadle to its clutching position.

6. In a safety mechanism for punch presses and the like, in combination: a driving pulley; a driving shaft; clutch mechanism for connecting said pulley and said shaft; a ram actuated by said shaft; a treadle; a connection between said clutch mechanism and said treadle comprising two 15 disengageable latch members; a cam for disengaging said latch members; and a rigid connection between said cam and said ram.

7. In a safety mechanism for punch presses and the like, in combination: a driving pulley; a driving shaft; clutch mechanism for connecting said shaft and said pulley; a ram actuated by said shaft and said pulley; a casing; two members slidably mounted in said casing, said members having 20 coöperating shoulders and adapted to

hold said members against relative endwise movement in one direction; springs for pressing one of said members into coöperating relation with the other of said members, said member acted upon by said springs 35 having a pin fixed therein; a cam arranged to engage said pin and to move said last-mentioned member out of coöperating relation with said other member; and means for operatively connecting said cam and said 40 ram.

8. In a safety mechanism for punch presses and the like, in combination: a driving pulley; a driving shaft; clutch mechanism for connecting said driving pulley and 45 said shaft; a ram actuated by said shaft; a treadle; a lever mounted on a fixed pivot; a connection between said lever and said clutch mechanism; a connection between said treadle and said lever comprising separable connecting members; a movable guard carried by said lever; means operated by said ram for separating said connecting members of the connection between said lever and said treadle; and means operated by said ram for 50 positively restoring said lever to its normal position.

WILLIAM A. D'ARCY.
WILLIAM S. ROBERTSON.
